10 Claims. (Cl. 123—179)

This invention relates to a hydraulic system for starting internal combustion engines.

It is known in the prior art to start internal combustion vehicle propulsion engines by the use of fixed displacement hydraulic motors. These motors are driven by pressure fluid supplied from a source, such as a pump, and in order to provide sufficient initial starting torque, large motors having a relatively high capacity are required. Such starting systems using fixed displacement hydraulic motors are rather inefficient in operation since it is difficult to match the torque characteristics of the motors with the starting torque characteristics of the internal combustion engines with which they are used. Although control means have been proposed for controlling the pressure of the fluid supplied to the motor to cause motor operation to approximate the torque requirements of the engine during starting, these control means are complex and expensive and tend to reduce the reliability of the equipment. Furthermore, multi-ratio gear trains with speed-changing means are often required to achieve satisfactory starting operation in systems utilizing fixed displacement motors.

The object of the present invention is to provide an improved hydraulic starting system utilizing a variable displacement hydraulic motor-pump unit which is driven as a motor by fluid supplied by a constant pressure source. The invention is characterized in that the rate of the fluid supplied by the source is less than the demand of the hydraulic unit at a predetermined speed less than starter cut-out speed. Pressure-responsive displacement control means are provided which maintain the motor torque constant at full rated value during an initial ignition period of the starting cycle (for example, until "light-off" occurs in the starting of a jet engine) and which, after this initial period, make use of the inadequacy of the source to automatically reduce displacement as the motor continues to accelerate the starter cut-out speed. In this manner, the torque curve of the hydraulic motor is caused to correspond rather closely with the starting characteristic of the internal combustion engine with the result that the size and weight of the motor is reduced, hydraulic power for driving the motor is conserved, and the need for an unusually large source of starting fluid and complicated gear trains is eliminated.

According to the preferred embodiment of the invention, the hydraulic motor-pump unit is of the rotary cylinder barrel longitudinally reciprocating piston "overcenter" type operable alternately either as a motor or as a pump. The unit includes a displacement control member movable between maximum stroke-establishing motoring and pumping positions on opposite sides of a zero stroke-establishing neutral position. The unit is designed to be driven as a variable displacement pump by the internal combustion engine after the latter is started and obtains independent operation. By causing the hydraulic starting unit to operate as a pump, the need for auxiliary pumping apparatus for supplying pressure fluid to auxiliary hydraulic loads of the vehicle is eliminated and the weight of the vehicle is reduced correspondingly.

As a safety feature of the invention, selectively operable stop means are provided for preventing the displacement control member from moving from its neutral position toward its maximum displacement-establishing motoring position when the hydraulic unit is being driven as a pump

2

by the internal combustion engine. These stop means prevent reversal of the pressure relationship between the two ports of the hydraulic unit.

The pressure-responsive displacement control means serve to vary displacement of the hydraulic unit during both the motoring and pumping operations. In the preferred embodiment of the invention, the pressure-responsive means include a dual-setting pilot valve which selectively establishes two "reference pressure" values against which the pressure at the high pressure port of the unit is compared. The lower of the reference pressure values is utilized to control hydraulic unit displacement during motoring and low pressure pumping operation, and the higher reference pressure value is utilized to control engine displacement during high pressure pumping operation.

Other objects and advantages of the present invention will become apparent from a study of the following specification when considered in conjunction with the accompanying drawings, in which:

FIG. 1 is a partly-sectioned elevational view of the hydraulic motor-pump unit used in the starting system of the present invention, the displacement control member being illustrated in its maximum stroke-establishing pumping position.

FIG. 2 is a schematic diagram of the hydraulic starting system, the displacement control member being illustrated in its maximum stroke-establishing motoring position.

Referring first to FIG. 1, the hydraulic motor-pump unit 3 is of the "overcenter" type operable alternately either as a motor or as a pump and includes a rotary group of elements consisting of a cylinder barrel having longitudinal bores therein and reciprocatory pistons mounted in said bores, said rotary group being mounted for rotation relatively to an angularly adjustable cam plate suspended in the unit housing. One type of such a hydraulic unit is disclosed in detail in the copending application of Tadeusz Budzich and Edward V. Manning, Serial No. 789,996, filed January 29, 1959, and entitled "Overcenter Hydraulic Starter Pump."

The hydraulic unit 3 comprises a housing 4 having a drive shaft 5 journaled therein to which is connected the rotary cylinder barrel 6. The rotary cylinder barrel 6 is in contiguous engagement at one end with the adjacent end face of stationary valve plate 7, which face contains radially-arranged arcuate high and low pressure ports in communication, respectively (through internal housing passages, not shown), with the housing high and low pressure outlet ports 8, 9 (FIG. 2) which extend in opposite radial directions from the right-hand extremity of the housing 4.

The cylinder barrel 6 contains a circumferential series of through longitudinal cylinder bores 11 which are arranged to register sequentially with the arcuate ports in the valve plate 7 as the cylinder barrel rotates. Pistons 12, formed with spherical heads 13 for connection with supporting shoes 14, are mounted in the cylinder bores for reciprocation by cam plate 15 and return plate 16.

The cam plate 15 is supported in housing 4 by cam plate yoke portions 15a and fixed housing trunnions 17 (FIG. 2) for pivotal movement about a horizontal axis normal to and intersecting the axis of drive shaft 5. The angular position of cam plate 15 determines the length of the strokes of pistons 12, and the cam plate is free to move between a maximum stroke-establishing motoring position (FIG. 2) and a maximum stroke-establishing pumping position (FIG. 1) located on opposite sides of a zero stroke-establishing neutral position (illustrated by the phantom lines in FIG. 2).

Spring means 19 are provided for biasing the cam plate 15 in the clockwise direction toward its maximum

stroke-establishing pumping position, as shown in FIG. 1. These spring means comprise a movable plunger 21 having a cylindrical axial projection 21a mounted for sliding movement in a bore 22 extending through a transverse wall 4a of the housing 4. Mounted for rotation in the free extremity of the plunger projection 21a is a spherical element 23 adapted to continuously engage cam plate 15. Preloaded spring 24, mounted concentrically about the plunger 21, reacts between the spring seat surface 25 of housing intermediate wall 4b and a rigid radial flange portion 21b of the plunger to urge the same to the right to pivot the cam plate in the clockwise direction.

Positioning motor 26 is arranged on the opposite side of the cam plate 15 from the spring-biasing means 19 and serves to pivot the cam plate in the counterclockwise direction against the biasing force of spring 24 toward the maximum stroke-establishing motoring position illustrated in FIG. 2. This positioning motor comprises a cylinder 27 rigidly secured to the housing 4 and containing a reciprocable piston 28. The piston is connected at one end with the cam plate 15 by the articulated connecting rod 29. Fluid is applied to the working chamber 26a of the motor through housing passage 31 to move piston 28 to the left in FIG. 1.

Selectively-operable cam plate stop means 32 are provided for preventing cam plate 15 from being moved by the positioning motor 26 from its zero stroke-establishing position toward its maximum stroke-establishing motoring position. These stop means comprise a fluid pressure motor consisting of a cylinder 33 rigidly connected with the housing 4 and a piston 34 mounted for reciprocation in said cylinder. The piston 34 is provided at one end with an axial projection 34a having a rounded end adapted to engage the cam plate 15. Passage 35 is provided for feeding pressure fluid to the working chamber of cylinder 33 to move the piston 34 to the left in FIG. 1.

The drive shaft 5 is connected, through internal gear trains (not shown) in the housing, with an intermediate shaft 36 which terminates in a splined coupling 37 connected with the power shaft of internal combustion engine 38 via mechanical connection 39.

Referring now to FIG. 2, the constant pressure fluid source 41, supplying hydraulic fluid, is connected with the housing high pressure port 8 through a first conduit 42 containing a flow restrictor 43 and a solenoid-controlled starter shut-off valve 44 operable between closed and open positions. The low pressure housing port 9 is connected with sump 45. As is conventional in hydraulic units of the overcenter motor-pump type, high pressure fluid is supplied from the source to the high pressure port 8 during motoring operation, and, during pumping operation, high pressure fluid is discharged from this same port.

The hydraulic starting system includes a dual-setting pressure-responsive pilot valve 46 which controls the operation of the positioning motor 26. The structure and operation of one embodiment of such a valve has been illustrated and described in detail in the Budzich et al. U.S. patent application Serial No. 789,996, filed January 29, 1959, referred to above. This pilot valve includes a housing having an inlet passage 47 connected with first conduit 42 via conduit 48a, a motor passage 49 connected with the working chamber 26a of positioning motor 26 via conduit 48b (which includes passage 31 of FIG. 1), and an exhaust passage 50 connected with sump 45 via conduit 51. The pilot valve housing includes a longitudinal bore in one end of which is mounted for reciprocation the movable valve plunger 52 having lands 53, 54 and 55 separated by grooves 56 and 57, respectively, for controlling the communication between the various valve housing passages. Through longitudinal slots 58 are provided in the outer periphery of land 53.

Mounted for reciprocation in the other end of the valve

housing bore is the spring seat 59. Preloaded spring 60, reacting between spring seat 59 and plunger 52, urges the seat toward a first position in which it abuts housing wall projection 61, and urges the plunger 52 in the opposite direction into engagement with the other bore end wall to effect venting of the working chamber 26a of positioning motor 26 via conduit 48b, passage 49, groove 57, passage 50 and conduit 51. The spring chamber 62 is in continuous communication with motor passage 49 via the plunger longitudinal and radial passages 63 and 64, respectively.

For high pressure pumping operation of the hydraulic unit 3, spring seat 59 is displaced longitudinally to a second position in which it abuts stop 65 to increase the preloading of spring 60 and thereby establish a second "reference pressure-establishing" condition of operation of the pilot valve 46. This shift of the seat 59 is caused by the fluid pressure in working chamber 46a which is varied by a solenoid-operated pressure selector valve 66. Valve 66 includes a housing having an inlet port 67 connected with high pressure port 8 via conduit 68a, a motor port 69 connected with the working chamber 46a via conduit 68b, and a pair of exhaust ports 70 and 71 connected with sump 45 via the branch lines of conduit 72. A reciprocable valve plunger 73, provided with lands 74 and 75 separated by groove 76, controls communication between the valve housing ports. An axial passage 77, extending into plunger 73 and terminating in a pair of radial passages 78, vents the chamber 88 at the left end of the plunger bore. Plunger 73 is biased to the right into contact with fixed stop 79 by coil spring 81 and, when the plunger 73 is in this position, inlet port 67 is closed by land 74 and spring seat working chamber 46a is connected with sump via conduit 68b, port 69, groove 76, port 70 and conduit 72.

Secured to one end of plunger 73 is the movable armature 85 of a stationary solenoid coil 86, the state of energization of which is controlled by switch 87. When this switch is open to deenergize the solenoid, plunger 73 assumes the position shown in FIG. 2. When solenoid 86 is energized by the closing of switch 87, armature 85 is moved to the left by magnetic attraction to shift plunger 73 to the left against the bias of spring 81 to a second position in which inlet port 67 communicates with outlet port 69 via groove 76, and exhaust port 70 is closed by land 75. This shift of plunger 73 permits pressure fluid from high pressure port 8 to flow to working chamber 46a where it is effective to move seat 59 into engagement with stop 65 and thus increase the loading of spring 60. As a result, pilot valve 46 is caused to operate at its second "reference pressure-establishing" condition.

Operation of cam stop motor 32 is controlled by a second solenoid-actuated valve 91. This valve includes a housing having an inlet port 92 connected with high pressure port 8 via conduits 93 and 68a, a motor port 94 connected with the working chamber 32a of stop actuating motor 32 via conduit 95 (which includes passage 35 of FIG. 1), and a pair of exhaust ports 96 and 97 connected with sump via the branch lines of conduit 98. Communication between these ports is controlled by a valve plunger 99 having lands 101 and 102 separated by groove 103. The plunger also contains axial and radial passages 104 and 105, respectively, serving to vent the chamber 110 at the left end of the plunger bore. Coil spring 106, mounted in the chamber 110, biases plunger 99 to a first position (shown in FIG. 2) in which land 101 closes inlet port 92 and groove 103 interconnects ports 94 and 96. In this position, working chamber 32a is connected with sump 45 via conduit 95, port 94, groove 103, port 96 and conduit 98. The plunger 99 is shifted to the left against the bias of spring 106 by a solenoid whose coil 108 is connected with switch 109 and whose armature is attached to the right end of the valve plunger. When switch 109 is closed to energize solenoid 108, the valve plunger is moved to a position in which exhaust

port 96 is closed by land 102 and inlet port 92 is connected with motor port 94 via groove 103. When valve plunger 99 is in this second position, pressure fluid is supplied from high pressure port 8 to the working chamber 32a of cam stop actuating motor 32 via conduit 68a, conduit 93, port 92, groove 103, port 94 and conduit 95.

During pumping operation of the hydraulic unit 3, fluid is supplied to the main hydraulic system of the vehicle via conduit 111 containing valve 112 which is operable between closed and open positions.

OPERATION

The operation of the hydraulic starting and pumping system may now be described. For the purposes of the following discussion, it will be assumed that the constant pressure source 41 comprises a pressure compensated pump regulated to deliver fluid at a maximum pressure of 3200 p.s.i. and having a control range extending between 3100 and 3200 p.s.i. According to the invention, the maximum capacity of this pump (which will be assumed to be 30 gallons per minute) is less than the maximum capacity of the hydraulic unit at starter cut-out speed (assumed to be 50 gallons per minute). Assume also that a pressure of 200 p.s.i. is required in positioning motor working chamber 26a to position the cam plate 15 in its maximum stroke-establishing motoring position against the bias of spring means 19, and that a pressure of 100 p.s.i. is required to maintain the cam plate in its zero stroke-establishing position. Finally it will be assumed that the first and second reference pressure values established by pilot valve 46 are 2900 and 3900 p.s.i., respectively, for causing the hydraulic unit to provide pumping pressures of 3000 and 4000 p.s.i., respectively.

1. Motoring operation

Assuming that valves 44 and 112 are closed and switches 87 and 109 are open, the initial preloading of spring 60 urges pilot valve plunger 52 to the left to vent positioning motor working chamber 26a via conduit 48b, passage 49, groove 57, passage 50 and conduit 51. Working chamber 46a behind spring seat 59 is vented to sump via conduit 68b, port 69, groove 76, port 70 and conduit 72, and working chamber 32a of the cam stop operating motor 32 is vented to sump via conduit 95, port 94, groove 103, port 96 and conduit 98. Cam plate 15 is positioned in its maximum stroke-establishing pumping position by spring means 19, as shown in FIG. 1.

As soon as starter shut-off valve 44 is opened, pressure fluid from constant pressure source 41 flows to high pressure port 8 through flow restrictor 43, valve 44 and conduit 42. The setting of flow restrictor 43 is based upon the flow of fluid required to obtain full displacement motoring at the ignition speed ("light-off" in the case of a jet engine) of the internal combustion engine.

Since the pilot valve inlet passage 47 communicates with conduit 42 via conduit 48a, the fluid pressure in passage 47 increases to exert a force on the left-hand end surfaces of lands 53 and 54 which displaces plunger 52 to the right against the bias of spring 60. Plunger 52 moves to the right until a lap position is reached in which land 54 interrupts communication between motor passage 49 and exhaust passage 50 to discontinue venting to sump of the working chamber 26a and spring chamber 62. The pressure required to hold plunger 52 in this lap position against the biasing force of spring 60 is the "reference pressure" against which the fluid pressure at high pressure port 8 is compared. Since spring seat 59 is in its FIG. 2 position, the first reference pressure value of 2900 p.s.i. is established and when the pressure in inlet passage 47 exceeds this value, plunger 52 moves further to the right to interconnect inlet passage 47 with motor passage 49 through slots 58 and groove 56. Pressure fluid is now transmitted to working chamber 26a through conduit 48b and to spring chamber 62 through radial and

longitudinal passages 64 and 63. When the pressure in these two chambers rises to a value at which the sum of the force of spring 60 and the pressure force acting on the right end of plunger 52 exceeds the pressure force acting on the left end of this plunger, the plunger 52 moves to the left toward its lap position. When it has again reached the lap position, the pressure established in working chamber 26a and spring chamber 62 will be equal to the difference between the pressure of fluid at high pressure port 8 and the "reference pressure." Further increases in pressure in conduit 42 produce equal increases in pressure in working chamber 26a and spring chamber 62.

As the pressure in inlet passage 47 progressively increases to 3200 p.s.i., the pressure in working chamber 26a progressively increases from zero to 300 p.s.i. and cam plate 15 is moved from its FIG. 1 position to its FIG. 2 position by the positioning motor 26. The pressure fluid applied from the source to high pressure port 8 is transmitted through the housing and valve plate passages to the cylinder barrel bores 11 to urge the pistons 12 to the left in FIG. 2, and the pistons react with the inclined cam plate 15 to apply torque to the cylinder barrel to drive the hydraulic unit 3 as a motor. Since the cam plate 15 is at its maximum stroke-establishing motoring position, the hydraulic unit operates initially at maximum displacement to drive the power shaft of the internal combustion engine 38 via mechanical connection 39.

For the purpose of the following discussion, "starter cut-out speed" is defined as being that speed of the motor at which the internal combustion engine is started and achieves independent operation, and "ignition speed" is defined as being the speed of the motor at which the engine is ignited (for example, "light-off" in the case of a jet engine). It will be assumed that "ignition speed" equals 60% of "starter cut-out speed."

As the hydraulic unit accelerates during motoring operation, a progressively increasing fluid demand is made on the source. For example, as the hydraulic unit accelerates from zero to ignition speed, the demand on the fluid source 41 increases from zero to 30 gallons per minute. Since the source 41 is a pressure compensated pump (as for example, a hydraulic unit similar to that of the present invention when it is operated as a pump), the source automatically increases its capacity in an effort to maintain system pressure. However, when the demand of the hydraulic unit exceeds the 30 gallon per minute maximum capacity of the source 41, the source no longer can maintain system pressure and this pressure drops below the lower limit (3100 p.s.i.) of the control range of the source. According to the present invention, the pressure-responsive displacement control means of the starter are now operable as a function of this decrease in system pressure (which occurs as the unit accelerates from 60% to full starter cut-out speed) for reducing unit displacement in an effort to maintain system pressure.

As the speed of the hydraulic unit increases further during motoring operation (for example, to 70% of starter cut-out speed), a greater quantity of hydraulic fluid is demanded by the hydraulic engine than is supplied through conduit 42 and the pressure drops momentarily at high pressure port 8. Assuming that the pressure at high pressure port 8 decreases to 3075 p.s.i., the pressure in conduit 48a and in inlet passage 47 drops accordingly with the result that the pressures in spring chamber 62 and working chamber 26a decrease to 175 p.s.i. Spring means 19 then pivots cam plate 15 slightly in the clockwise direction to reduce the displacement of the hydraulic unit to correspond to the rate of flow of fluid in conduit 42. As the speed of the hydraulic engine increases further (for example, to 80% of starter cut-out speed), the pressure at high pressure port 8 decreases (for example, to 3050 p.s.i.), the pressure in working chamber 26a decreases to 150 p.s.i., and the cam plate 15 is displaced in the clockwise direction by spring

means 19 to further reduce hydraulic unit displacement. This sequence of events continues as the internal combustion engine accelerates until, at starter cut-out speed, the pressure at port 8 decreases to 3000 p.s.i. and the pressure of working chamber 26a decreases to 100 p.s.i. When the pressure in working chamber 26a decreases to this value, cam plate 15 is positioned in its zero stroke-establishing position illustrated by the phantom lines in FIG. 2. The internal combustion engine has now been started and obtains independent operation.

2. Pumping operation

After the internal combustion engine has accelerated to the point that it develops sufficient power to drive the hydraulic unit as a pump, solenoid-controlled valve 44 is closed to isolate the system from the fluid source 41 and as a result of the fluid leakage which occurs in the hydraulic unit, the pressure at high pressure port 8 momentarily drops slightly below 3000 p.s.i. and the cam plate 15 is displaced slightly overcenter on the pumping side of neutral so that the hydraulic unit pumps sufficient fluid to bring the pressure at high pressure port 8 up to the 3000 p.s.i. operating pressure. Closing of switch 109 causes plunger 99 to move to the left whereupon fluid is applied to stop motor working chamber 32a from high pressure port 8 via conduit 68a, conduit 93, port 92, groove 103, port 94 and conduit 95. Cam stop 34a is displaced to the left to prevent cam plate 15 from moving in the counterclockwise direction from its natural position toward its maximum stroke-establishing motoring position.

Since the hydraulic unit is now being driven as a pump to supply fluid at a pressure of 3000 p.s.i. from port 8, the pressure in inlet passage 47 is 3000 p.s.i. and the pressure in working chamber 26a is 100 p.s.i. and the cam plate is positioned in its zero stroke-establishing neutral position. When valve 112 of the auxiliary hydraulic system supply line 111 is opened, a flow demand is created and the pressure in inlet chamber 47 decreases (for example, to 2990 p.s.i.). The pressure in working chamber 26a decreases to 90 p.s.i. and cam plate 15 is pivoted in the clockwise direction by spring means 19 to increase displacement of the hydraulic unit in an effort to bring the system pressure up to 3000 p.s.i. When the system pressure is again returned to this operating pressure, cam plate 15 is returned to its zero stroke-establishing position by the positioning motor 26. If the system demand increases further to reduce the pressure to 2900 p.s.i., the pressure in working chamber 26a decreases to zero and the cam plate is positioned in its maximum stroke-establishing pumping position. As the system pressure is brought up to 3000 p.s.i., the cam plate 15 is progressively returned to its zero stroke-establishing position. In the event that a very large system demand is presented which causes system pressure to drop below the reference pressure value of 2900 p.s.i., plunger 52 is no longer maintained in its lap position against the bias of spring 62, and the spring urges plunger 52 to the FIG. 2 position to vent working chamber 26a. Cam plate 15 is maintained in its maximum stroke-establishing pumping position by spring means 19 and the hydraulic engine operates continuously at maximum displacement in an effort to bring the system pressure up to its operating value. When the system pressure increases above 2900 p.s.i., plunger 52 is operated to again connect working chamber 26a with high pressure port 8, and cam plate 15 is moved toward its zero stroke-establishing position.

In order to provide a higher system operating pressure (for example, 4000 p.s.i.) during operation of the hydraulic motor-pump unit, the pilot valve is operable to establish a second "reference pressure" value (for example, 3900 p.s.i.) which is greater than the first reference pressure value. This accomplished by closing switch 87 to displace the pressure selector plunger 73 to the left to apply pressure fluid from high pressure

port 8 to the spring seat working chamber 46a via conduit 68a, port 67, groove 76, port 69 and conduit 68b. Spring seat 59 is displaced to the left against stop 65 to increase the preloading of spring 60 and thus establish the second reference pressure against which the pressure at high pressure port 8 is compared. Plunger 52 is urged to the left by spring 60 to vent working chamber 26a and cam plate 15 is positioned at its maximum stroke-establishing position by the spring means 19. As the pressure at high pressure port 8 now increases to 3900 p.s.i., the pressure in inlet chamber 47 increases correspondingly to move plunger 52 to its lap position. As the pressure at high pressure port 8 increases to 4000 p.s.i., the pressure in working chamber 26a increases to 100 p.s.i. to position cam plate 15 in its zero stroke-establishing position. If the system demand causes the pressure at high pressure port 8 to decrease momentarily (to 3990 p.s.i., for example), cam plate 15 is moved to the right slightly to increase displacement and to bring the system pressure back to 4000 p.s.i., at which time the cam plate is returned to its zero stroke-establishing position. Consequently, during pumping operation, the hydraulic unit operates as a pressure-compensated variable displacement pump tending to maintain an operating pressure of 4000 p.s.i. when the control valve establishes a reference pressure of 3900 p.s.i. and an operating pressure of 3000 p.s.i. when the control valve establishes a reference pressure of 2900 p.s.i.

In order to return the hydraulic unit 3 to motoring operation, switches 87 and 109 are opened, valve 112 is closed and solenoid-controlled valve 44 is opened. The motoring and pumping operations are then repeated in the manner described above.

It is important to note that although the flow restrictor 43 has been illustrated and described as being arranged intermediate the source 41 and the solenoid-controlled valve 44, the restrictor could be included equally as well within the actual starter control system. Furthermore, a flow restrictor need be provided only when the capacity of the source is greater than the demand of the motor-pump unit when it is operated as a motor at a predetermined speed (i.e., at the ignition speed of the internal combustion engine) which is less than starter cut-out speed. In inherently flow-limited systems using a source of limited capacity (i.e., a source which supplies fluid at a rate insufficient to meet the demand of the hydraulic motor at ignition speed of the internal combustion engine), the use of a flow restrictor is not necessary to obtain the starter control operation of the present invention. However, from a practical standpoint it appears desirable to incorporate the flow restrictor even in inherently flow-limited systems, since auxiliary fluid supplies are often used and since bench testing of the starter system can be performed more readily if the flow restrictor is an integral part of the device.

While in accordance with the provisions of the patent statutes we have illustrated and described the best form and embodiment of the invention now known to us, it will be apparent to those skilled in the art that other changes may be made in the apparatus described without deviating from the invention set forth in the following claims.

What is claimed is:

1. A hydraulic starting system for accelerating an engine to starter cut-out speed comprising
  - (a) a variable displacement hydraulic motor having a displacement control element which is movable between minimum and maximum displacement-establishing positions;
  - (b) a source of hydraulic fluid capable of delivering fluid at a substantially constant pressure and at a rate which varies between a minimum value and a maximum value equal to the demand of the motor when it is running at a certain speed less than cut-

out speed and its displacement control element is in maximum displacement-establishing position;
(c) conduit means connected with the motor and the source for leading fluid from the source to and through the motor; and

(d) motor control means, independent of the source, connected with the displacement control element and responsive to the flow demand of the motor for positioning said element in the maximum displacement-establishing position when the motor is running and the demand is below said maximum delivery rate and for moving said element toward the minimum displacement-establishing position as the flow demand tends to increase above said maximum delivery rate, whereby the change in displacement of the motor maintains motor demand substantially constant at the rate of demand at said certain speed.

2. A hydraulic starting system for accelerating an engine to starter cut-out speed comprising

(a) a variable displacement hydraulic motor having a displacement control element movable between minimum and maximum displacement-establishing positions;

(b) a source of hydraulic fluid, including a variable delivery, discharge pressure compensated hydraulic pump, capable of delivering fluid at a substantially constant pressure and at a rate that varies between a minimum value and a maximum value equal to the demand of the motor when the motor is operating at a certain speed less than cut-out speed and the displacement control element is in the maximum displacement-establishing position;

(c) conduit means connected with the motor and the source for leading fluid from the source to and through the motor; and

(d) motor control means connected with the displacement control element and responsive to the operating pressure of the motor for positioning said element in the maximum displacement-establishing position when operating pressure is above a predetermined value and for moving said element toward the minimum displacement-establishing position as the operating pressure tends to decrease below said predetermined value, whereby the change in displacement of the motor maintains motor demand constant at said maximum delivery rate.

3. A hydraulic starting system as defined in claim 2

(a) in which the maximum displacement of the pump is greater than said maximum value; and

(b) which includes flow limiting means interposed in the conduit means between the source and the motor for limiting the rate of supply to the motor to said maximum value.

4. A hydraulic starting system as defined in claim 3 in which the motor control means comprises

(a) spring means biasing the displacement control element toward the minimum displacement-establishing position;

(b) a fluid pressure positioning motor connected with the displacement control element for moving said element toward the maximum displacement-establishing position; and

(c) a pilot valve responsive to the operating pressure of the motor for pressurizing the positioning motor a certain amount sufficient to cause it to move the displacement control element to the maximum displacement position when the operating pressure is above said predetermined value and for reducing the pressure in the positioning motor below said certain amount as the operating pressure tends to decrease below said predetermined value.

5. A hydraulic starting and pumping system for accelerating an engine to starter cut-out speed and for supplying fluid under pressure comprising

(a) a variable displacement hydraulic motor-pump

unit of the overcenter type having high and low pressure ports and a displacement control element movable between first and second maximum displacement-establishing positions on opposite sides of a zero displacement-establishing position;

(b) a reservoir connected with the low pressure port;

(c) a source of hydraulic fluid, including a variable delivery, discharge pressure compensated hydraulic pump, connected with the unit and capable of delivering fluid at a substantially constant pressure and at a rate that varies between a minimum value and a maximum value equal to the demand of the motor-pump unit when that unit is operating at a certain speed less than cut-out speed and the displacement control element is in the first maximum displacement-establishing position;

(d) a first shut-off valve for connecting and disconnecting the source and the motor-pump unit;

(e) a delivery conduit connected with the high pressure port;

(f) a second shut-off valve located in the delivery conduit for opening and closing same; and

(g) control means connected with the displacement control element and responsive to the operating pressure of the unit for positioning the displacement control element in the first maximum displacement-establishing position when the pressure is above a predetermined value and for moving the displacement control element toward the second maximum displacement-establishing position as the pressure tends to decrease below said predetermined value.

6. A hydraulic starting and pumping system as defined in claim 5 including

(a) stop means for preventing the displacement control element from moving from the zero displacement-establishing position toward the first maximum displacement-establishing position; and

(b) means connected with the stop means for selectively rendering it effective and ineffective.

7. A hydraulic starting and pumping system as defined in claim 5 in which the control means comprises

(a) spring means biasing the displacement control element toward the second maximum displacement-establishing position;

(b) a fluid pressure positioning motor connected with the displacement control element for moving said element toward the first maximum displacement-establishing position; and

(c) a pilot valve responsive to the operating pressure of the unit for selectively pressurizing and venting the positioning motor, respectively, as the pressure rises above and decreases below said predetermined value.

8. A hydraulic starting and pumping system as defined in claim 7 including selector means connected with the pilot valve for causing the pilot valve to pressurize and vent the positioning motor, respectively, as the pressure rises above and decreases below a pressure higher than said predetermined value.

9. The method of accelerating an engine to starter cut-out speed using a variable displacement hydraulic motor comprising

(a) generating fluid under pressure and supplying same to the motor to cause it to accelerate the engine;

(b) maintaining supply pressure substantially constant as the rate of supply is varied from a minimum value to a maximum value;

(c) operating the motor at maximum displacement until the engine accelerates to a certain speed less than cut-out speed;

(d) starting the engine at least by the time it reaches said certain speed so that it commences to develop torque;

(e) limiting the rate of supply of fluid to the motor to the rate demanded by the motor at said certain speed; and

(f) thereafter reducing the displacement of the motor as the engine accelerates to starter cut-out speed to thereby maintain the flow demand of the motor substantially constant at the rate demanded by it at said certain speed.

10. The method of accelerating an engine to starter cut-out speed using a variable displacement hydraulic motor comprising

(a) generating fluid under pressure and supplying same to the motor to cause it to accelerate the engine;

(b) regulating the rate of generation of fluid under pressure in accordance with the demand of the motor to thereby maintain supply pressure substantially constant;

(c) operating the motor at maximum displacement until the engine accelerates to a certain speed less than cut-out speed;

(d) starting the engine at least by the time it reaches said certain speed so that it commences to develop torque;

(e) limiting the rate of supply of fluid to the motor to the rate demanded by the motor at said certain speed; and

(f) thereafter reducing the displacement of the motor as the engine accelerates to cut-out speed to thereby maintain the flow demand of the motor substantially constant at the rate demanded at said certain speed.
